UNITED STATES PATENT OFFICE

EVERETT H. HOLLINGSHEAD, OF DAYTON, TEXAS

LINE MARKER

Application filed June 7, 1929. Serial No. 369,026.

The invention relates to an apparatus for marking lines and is particularly useful on highways, streets and the like, although it is adapted for other purposes as will be obvious from the specification which follows.

It is an object of the invention to provide an apparatus for making a center line upon roadways, particularly the line used to separate the traffic upon the road. It is also useful in marking off parking areas along streets or for other similar purposes.

It is a further object of the invention to provide a device capable of handling either paints or heated liquids such as asphalt which are to be used for marking purposes.

Another object of the invention is to arrange the device so that it will feed a continuous supply of liquid to the distributor or marking shoe at a uniform rate.

Still another object of the invention is to arrange the marking shoe in an adjustable position such that it will not vary from the center line upon slight variations of the traction apparatus.

Another object of the invention is to provide an overflow device which will prevent the waste of the liquid.

Another object of the invention is to arrange the distributor or marking shoe in such a manner that the liquid may be shut off closely adjacent the discharge opening.

A still further object is to provide the device with an arrangement of jacket which retains the heat about the distributor shoe as well as the storage tank.

Other and further objects of the invention will be readily apparent to those skilled in the art when the following description is considered in connection with the accompanying drawing.

Fig. 1 is a side elevation of a complete apparatus showing the various parts and having one of the wheels broken away for purposes of clearness.

Fig. 2 is a rear elevation of the marker shoe and housing disclosing the arrangement of the burner and valve structure.

Fig. 3 is a side elevation of the support member used to control the elevation of the discharge shoe.

Fig. 4 is a side elevation of the discharge nozzle.

The present invention is an improvement over the apparatus disclosed in my prior co-pending application Serial No. 246,413, filed January 13, 1928.

Fig. 1 shows a vehicle comprising a single front wheel 1, and bearing 2 therefor. The wheel is adapted for rotation in the bearing 2 and is guided by means of a pair of spaced rods 3 connected to a cross member 4, which in turn is fastened to the post 5.

A steering lever 6 is shown as extending rearwardly from the post 5 and resting upon a rack 7. It seems obvious that by manipulation of the steering lever 6 that the machine may be guided down the road or wherever desired. The bearing 2 supports a pair of side members 10 which extend rearwardly and rest upon the rear wheels 11. These frame members 10 support the tank 12 adapted to contain a supply of fuel. A pull bar 13 is shown as extending forwardly of the bearing 2 so that the device may be attached to any motor vehicle or the like by which it may be propelled.

Supported on the frame members 10 is a jacketed tank 15 for the marking liquid, which may be paint, asphalt or any suitable material.

The discharge of the liquid from the tank 15 is accomplished by means of the control valve 20. This valve is arranged for sliding movement within a pipe 21 and is controlled by means of the lever arm 22, which extends rearwardly for manipulation by the operator. In this manner by pushing downwardly upon the lever 22 the valve pin 20 is raised and permits the escape of the liquid into the discharge shoe. This shoe is shown in rear elevation in Fig. 2 and comprises a jacket member 25 which surrounds the container 26. It will be seen in Fig. 1 that the jacket member 25 is adapted to slide within a somewhat similar member 27, which is supported from the tank 15.

A burner 28, which is arranged for either gasoline, kerosene or fuel oil of any type, is shown as mounted adjacent the jacket 25 and arranged so that heat may be applied to the

5 container 26. This heat as it passes about the container 26 will arise thru the jacket 25 and into the similar member 27 where it will pass into the jacket about the tank 15 and 5 will not be dissipated. A second burner 29 is shown as used for applying heat inside the jacket about the tank 15. These burners are used when it is desired to distribute asphalt or other material in heated condition. When 10 paint is being distributed these burners are not necessary. Both the jacket member 25 and the container 26 are shown as supported upon a pair of bars 30, which are pivoted at 31. A suitable brace member 32 is shown as 15 connecting the support for the bars 30 and the frame members 10 so that a sturdy construction is obtained. The rear end of the bar members 30 carry a pin 33 to which is connected a support rod 34, which in turn 20 is connected to the adjustment lever 35. This lever 35 is shown as pivoted to the rack 7 and may be arranged in any desired position by means of a quadrant and latch 36. It will be apparent from this structure that 25 by adjustment of the handle 35 the elevation of the shoe with respect to the surface being marked, which is indicated at 37, may be had. When the handle 35 is moved downwardly the distributor shoe will be raised upwardly 30 but will pivot about the pin 31. The rod 34 is shown as of a special construction to allow limited movement of the distributor shoe in passing over irregularities in the surface being marked. This connection is shown in Fig. 35 3 where the rod 34 extends into a sleeve 38 and is adapted to slide down upon a bolt 39, which is placed in the slot 42 within the rod 34.

40 The rod 34 also carries a stop pin 40, which is arranged to restrain one end of a coil spring 41, the other end of which abuts against the sleeve 38. In this manner, regardless of the adjusted position of the handle 35, the sleeve 38, which is connected to the 45 pin 33, will be free for limited vertical movement when irregularities are encountered by the shoe.

45 The distributor shown is of a particular construction and consists of a valve housing 45, which is connected to the bottom end of the container 26. This valve housing contains a cylindrical valve 46, having a longitudinal slot 47 therein. This valve is reduced at 48 to receive an arm 49, which arm 50 is fastened upon the reduced portion 48 in any desired manner so that rotation of the arm 49 will also rotate the valve 46. Connected to this arm 49 is a rod 50, which is 55 shown in Fig. 1 as extending upwardly to a handle 51 convenient for the operator. It will be seen that by pulling upon the handle 51 the cut-off valve 46 will be rotated and the position of the slot 47 controlled. Below the valve structure 45 is the contact 60 shoe or nozzle 55. This is shown as a block

of any suitable material having a passage 56 therein. The slot 47 of the valve 46 is adapted for alignment with this passage 56 and when in this position, such as shown in Fig. 4, will permit a flow of liquid to the surface 37. As previously described, the flow of liquid may be instantly cut off by manipulation of the handle 51 to rotate the slot 47 out of alignment with the passage 56. 75

The block or nozzle 55 is shown as formed with slanting faces and the passage 56 parallel to these faces. This is of advantage as these blocks soon wear away in constant use so that the leading and trailing surfaces in the present block will remain of the same 80 width as the block wears away and no adjustment except of the handle 35 is necessary to take care of the wear.

85 By adjustment of the valve 20, by movement of the handle 22, the flow of fluid into the container 26 may be controlled. A considerable supply of fluid is usually maintained in the container 26, and, as shown in Fig. 1, I have provided means visible to the operator to determine when the container 26 90 is about to overflow. This means consists of a rearward extension 58 upon the container 26. Upon this extension is mounted an overflow pipe 59, adapted to carry a bucket 60. Thus when the level of the fluid in 95 the container 26 reaches that of the top of the overflow pipe, the operator will notice the flow of liquid into the bucket 60 and then may adjust the valve 20 to reduce the flow of liquid from the tank. The bucket 60 prevents the overflow from falling onto the roadway and disfiguring the line being marked. 100

105 In marking various highways the type of the material from which the highway is constructed varies greatly, some surfaces being pitted and rough, whereas other surfaces may be quite smooth. Upon the nature of the surface being marked depends the amount of liquid to be discharged, and I have provided an adjustment of the distributor shoe to permit the escape of any desired amount of liquid. This adjustment is shown at 70 and comprises a rod 71, which is connected at 72 to the forward side of the distributor shoe. By adjustment of the nuts 73 the base of the shoe may be moved forwardly or rearwardly as desired. It is obvious that when the base 74 of the shoe is in contact with the surface 37 that but a small amount of liquid may escape, but if the shoe is moved forwardly or rearwardly the shoe will rest at an angle on the surface 37 and a greater amount of liquid may escape. 110

115 From the foregoing description it will be apparent that I have provided means to adjust the distributor shoe both vertically and horizontally, so that irregularities in the road may be overcome by vertical adjustment and the amount of liquid be controlled by horizontal adjustment. 120

The particular placing of the distributor shoe adjacent the rear traction wheels 11 is of material advantage as it will be seen that any variation of the wheel 1 from the line 5 being marked will be materially reduced, due to the fact that the marking shoe is spaced a considerable distance therefrom and is adjacent the support wheels 11 so that any side movement will be reduced in proportion to 10 its distance from the wheels 11 as compared with the distance between the wheels 1 and 11. In this manner a substantially straight line is marked regardless of slight variations in the steering of the apparatus.

15 Another point of advantage is the pivoting of the support bars 30, which carry the discharge shoe at a point in front of the wheels 11 and considerably in the rear of the wheels 1. In this way, if the wheel 1 strikes an irregularity the shoe is not raised from the surface for the reason that the bars 30 are pivoted substantially in the middle of the apparatus and the vertical movement of the pin 31 is reduced to a minimum. Thus when 20 either the forward or the rear wheels pass over an obstruction the shoe 55 is affected but slightly. In this way no blotches or disfigurement of the line being marked occurs.

25 When it is desired to stop the machine, manipulation of the handle 51 closes the valve 46 and only the liquid remaining in the pas-

sage 56 may pass out onto the pavement, it being the object of this construction to place the valve 46 as near the point of marking as possible, so that when a halt in the operations is necessary no liquid will be wasted and no disfigurement of the line will occur. As the 70 valve 46 is closed, movement of the machine but a short distance will discharge the liquid in the passage 56 and not blot the roadway.

The foregoing description sets forth what I believe to be a practical embodiment of my invention but it is obvious that slight variations may be made without departing from the spirit of my invention.

Having described my invention, what I claim as new is:

In a marking apparatus, a supply tank, a discharge container, a valve operable to control the flow of liquid from said tank, an overflow line for said container, a cutoff valve below said container to prevent escape of liquid therefrom, and a discharge nozzle below said valve and adapted to contact the surface being marked, said nozzle including a block of rigid material with substantially 85 thick walls inclined rearwardly and having 90 a passage therethrough for marking material.

In testimony whereof I hereunto affix my signature this 23 day of May, A. D. 1929.

EVERETT H. HOLLINGSHEAD.
